(57) **CLAIM**

The ornamental design for a burial stretcher for transporting columbarium, as shown and described.

DESCRIPTION

1. Burial stretcher for transporting columbarium
 1.1 is a perspective view of a burial stretcher for transporting columbarium embodying my new design;
 1.2 is a front elevation view thereof;
 1.3 is a rear elevation view thereof;
 1.4 is a right side elevation view thereof;
 1.5 is a left side elevation view thereof;
 1.6 is a top plan view thereof; and
 1.7 is a bottom plan view thereof.

The broken line showings of the columbarium and urn illustrate environmental structures and form no part of the claimed design.
